UNITED STATES PATENT OFFICE.

CLARENCE S. LEE, OF HAMILTON, ONTARIO, CANADA.

KEY AND CARD CONTAINER.

Application filed October 22, 1927. Serial No. 228,027.

This invention relates to combined key and identification card containers comprising a backing and closure flaps, a card envelope consisting of transparent material marginal-
ly bound and stitched to the backing, a protective flap hinged to the backing for covering the card envelope, and a gang of key hooks mounted on the protective flap and backing.

10 The principal object of the invention is to provide a suitable combined key and identification card container, the purpose in view being that the owner's keys and identification card accompany each other as a unit.

15 Another important object is to provide a device of the class specified which will be simple, durable, efficient, and inexpensive to manufacture.

These, together with other objects, may be 20 attained by the construction, combination, and arrangement of the parts as will be hereinafter more fully described, illustrated in the accompanying drawing, and ascertained in the claim hereunto annexed.

25 Referring to the drawing:

Figure 1 is a perspective view of a combined key and identification card container constructed in accordance with this invention, showing the closure flaps open for use and the protective flap partially turned up so as to disclose a portion of the envelope beneath:

Figure 2 is a front view of the container as when completely closed; and,

Figure 3 is a diagrammatic cross-sectional 35 side elevation of the container taken on the line 3—3 in Figure 2.

Similar reference numerals refer to corresponding parts throughout the several views.

This invention is particularly serviceable 40 for containing the owner's automobile permit card as well as his keys, it being desirable that the former is upon no occasion out of his possession, and as his automobile key is almost invariably carried amongst his other important keys, the use of this device assures 45 the presence of the permit when his automobile is being driven, although it is understood

that for non-automobile-operators the device will be useful for containing, as well as keys, club or society identification cards and the like.

The invention in its preferred form consists of the backing 10 flanked by the hinged closure flaps 11, which, when closed, are folded parallel to said backing so that they overlap and are secured by a suitable fastening device, such as the dome fastener 12.

On the inner side of the backing 10 is the card envelope consisting of the transparent material 13, such as celluloid, set in the marginal binding or bezel 14, and open at one side. An automobile permit card 15 is shown as contained in said envelope.

Covering the celluloid envelope 13 is the protective flap 16, and jointly secured to this flap and to the backing 10 is the key hook plate 17 which carries the gang of key hooks 18. This protective flap is for the purpose of protecting the celluloid envelope 13 from damage from keys suspended on the key hooks 18, and is adapted to swing outwardly from the bottom of the key hook plate 17 in order to disclose the permit card when required.

There has thus been produced a simple and useful device of the class described and for 75 the purpose specified, and now having fully described the invention and the manner in which it is to be performed in such manner that any person could construct and use the same, I claim:—

In a combined key and card container, a backing, hinged closure flaps flanking the backing, a sheet of transparent material fastened on the inside of the backing and open at one edge forming an envelope, a protective 85 flap hinged relative to the backing and covering said envelope, and a gang of key hooks disposed in an upper location in the container so that the keys suspended thereby are interposed between the protective flap and said closure flaps when the latter are closed.

In testimony whereof he has affixed his signature.

CLARENCE S. LEE.
